Primary Examiner — Elizabeth J Oswecki(74) *Attorney, Agent, or Firm* — QuickPatents; Kevin Prince(57) **CLAIM**

The ornamental design for an artificial steel flower, as shown and described.

DESCRIPTION

FIG. 1 is a top perspective view of an artificial steel flower, showing our new design;

FIG. 2 is a front perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and,

FIG. 9 is a bottom perspective view thereof.

The broken lines in illustrating words in FIG. 9 form no part of the claimed design and have been disclaimed.

1 Claim, 4 Drawing Sheets(56)
